UNITED STATES PATENT OFFICE.

RICHARD P. WEAVER, OF CARLISLE, PENNSYLVANIA.

REVERSIBLE FROG.

1,391,226.

Specification of Letters Patent. Patented Sept. 20, 1921.

Application filed November 27, 1920. Serial No. 426,738.

To all whom it may concern:

Be it known that I, RICHARD P. WEAVER, a citizen of the United States, residing at Carlisle, in the county of Cumberland and

5 State of Pennsylvania, have invented certain new and useful Improvements in Reversible Frogs, of which the following is a specification, reference being had to the accompanying drawings.

10 This invention relates to railway frogs, and particularly to sectional frogs.

The general object of the invention is to provide a railway frog that will have double the life of an ordinary frog, and in this connection to form the frog of a plurality of sections, one of said sections forming the body of the frog, and upon which the wear comes, the other section forming splice bars holding the body of the frog in place on the 20 track, the body of the frog being reversible so that thereby after the body of the frog has been worn upon one face, the frog body may be reversed so as to substitute a new and unworn face.

25 A further object is to provide a construction of this character in which the splice bars are formed with means for supporting that portion of the body of the frog which is reduced in thickness and which has to 30 bear the weight of the train, thus preventing any chance of the body of the frog being broken.

35 A further object is to provide a construction of this character in which the splice bars and the frog body are formed with alining transversely extending bolt openings whereby the splice bars and the body of the frog may be bolted together and rigidly held in correlated position.

40 Other objects will appear in the course of the following description.

My invention is illustrated in the accompanying drawings, wherein:—

Figure 1 is a top plan view of the frog 45 assembled;

Fig. 2 is a perspective view of the middle portion of the body of the frog;

Fig. 3 is a section on the line 3—3 of Fig. 1;

50 Fig. 4 is a section on the line 4—4 of Fig. 1;

Fig. 5 is a section on the line 5—5 of Fig. 1;

Fig. 6 is a section on the line 6—6 of 55 Fig. 1;

Fig. 7 is a perspective view of one of the lateral sections of the frog;

Fig. 8 is a perspective view of the other lateral section.

Referring to these drawings, it will be seen that the frog is composed of a body portion, designated generally A, and two splice bars or lateral sections, designated B and C. These three sections are preferably cast of manganese or alloy steel, though naturally I do not wish to be limited to the use of this material for the purpose. The body A of the frog is an integral casting and is formed as illustrated in Fig. 2 and in the sectional views in Figs. 3 to 6. This body is cast or otherwise formed to provide upon its upper and lower faces a medially disposed, longitudinally extending or longitudinally tapering tread portion 10. This portion 10 tapers toward the end 11, this sharp end 11 terminating short of the end of the body A. The opposite end of this tapering transversely flat tread portion is designated 12 and is relatively wide, and from this butt end 12 of the tapered portion extends a tapered extension 13 whose upper face is below the level of the upper face of the portion 10, the opposite faces of the portion 10 being recessed, as at 14, to this level of the portion 13. The lateral faces of the portion 13 are longitudinally ribbed to fit against the webs of rails E, and this portion 13 is transversely perforated, as at 15, with bolt holes.

Extending laterally from the portion 10 are webs 16 which begin inward of the butt end 12, these webs being less in thickness than the thickness of the portion 10, illustrated most clearly in the section in Fig. 5. The ends of these webs 16 are curved inward, as at 17, and merge into the side faces of the portion 10 adjacent the butt end thereof. The web 16 extends from the point 17 to the opposite extremity of the frog remote from the end 12 of the portion 10, and formed on the opposite faces of these webs 16 are the oppositely projecting flanges 18 and 18^a, as shown most clearly in the sectional views in Figs. 3 to 5. These flanges at their ends adjacent the butt end of the portion 10 are outwardly curved or flared with relation to each other and the portion 10, and from this point extend inward and into approximately parallel relation to the tapering portion 10 until they reach a point 110

somewhat beyond the extremity 11 of the portion 10, and then these flanges diverge slightly from each other, leaving a throat 19. From a point in proximity to the point 5 11 to the adjacent extremity of the frog these flanges are gradually widened. The opposite side edges of the flanges 16 and the opposite side edges of the portion 10 beyond the flanges 16 are longitudinally recessed, as 10 at 20, and this body portion A is formed with a plurality of transversely extending bolt holes 15, as heretofore described, for the part 13, these bolt holes being adapted to receive the bolts whereby the splice bars 15 B and C are held to the body A. It will be seen that this body A is identically formed upon its upper and lower faces so that either face of this body portion A may be turned upward to support the strain of a railway 20 train. The part 13 is to receive and be bolted to the converging rails of the track. The part 10 is a tread portion of the frog, as are the relatively wide portions of the flanges 18. The splice bars B and C are different in 25 detailed formation but are substantially alike in that they are formed to engage the opposite side edges of the body A, interlock therewith, and be fastened thereto by transversely extending bolts to form lateral exten- 30 sions of the body A. The splice bar C is, generally speaking, like an elongated fish plate or the ordinary splice bars used on railways, except that it is curved or angled to fit against the side face of the body A. The splice bar C has a laterally projecting 35 flange 21 bearing upon the ties in the same manner as the flange of a railway rail and adapted to be held to the ties by the overhanging spike heads. The inner face of the splice bar is formed with a longitudinally 40 extending rib 22 which extends into the recess or groove 20 formed along the entire side edge face of the body A. The splice bar C is also formed with a series of elongated apertures 23 for the passage of bolts 45 24 heretofore referred to as passing through the openings 15, these elongated apertures being adapted to align with the openings 15. The vertical portion of the splice bar ex- 50 tends from a point beyond one end of the body A to a point approximately at the junction of the curved edge face 17 of the web 16 with the edge face of the end 12 of the portion 10, but this splice bar is formed 55 with a horizontally disposed web 25 which extends laterally inward from a point about the middle of the splice bar C and extends beyond the butt end 26 of the splice bar. This web 25 is provided at the reentrant 60 angle 27 of the splice bar with a longitudinally extending tapered rib or boss 28, and the web 25 at its rear corner is also provided with an upwardly extending relatively narrow boss or protuberance 29. That portion 65 of the splice bar C which projects be-

yond the body A is formed like a fish plate to engage a rail of the track and is perforated, as at 30, for the passage of the ordinary fish plate bolts. The splice bar B is substantially the same in form as the splice 70 bar C. It also is provided with the horizontally extending lateral flange 21, with the inwardly projecting rib 22, with the slots 23 for the passage of bolts 24, and with a web 25 having thereon the longitudinally 75 extending somewhat tapered boss 28 and with the boss 29 at the inner corner of its butt end, but this splice bar B differs from the splice bar A, in that it is also provided with an integral web 31 adjacent the end 80 remote from the lug or boss 29, this web projecting out farther than the web 25 and being formed with a longitudinally extending rib or boss 32. This web 31 is joined to the web 25 by a relatively narrow, longitudinally extending web 33. It will be understood that the webs 25 of both splice bars extend beneath the body A, as does the web 31. Both of the webs 25 of both splice bars are provided with an upwardly projecting flange 26^a at the butt end of the splice bar which is much lower than but forms a continuation of the main vertical web of the splice bar, as illustrated most clearly in Fig. 6. 95

When these three sections of the frog are engaged with each other, as shown in Fig. 1 and the sectional views in Figs. 3 to 6, the web 31 extends beneath the body A and the rib 32 extends upward in the space between 100 the downwardly projecting flanges 18^a of the body and bears against the under face of the web 16 so as to form a support for this web against crushing or breaking strains. The splice bar C is also formed at the point 105 opposite the web 31 with a slightly projecting web 34 extending beneath the adjacent flange 18^a, as shown most clearly in Fig. 3. Adjacent the point where the section line 4-4 crosses there are no supporting lugs, 110 protuberances or bosses because the body is relatively narrow at this point and is provided with the centrally disposed projecting portions 10 and 10^a on its opposite faces and with the closely adjacent laterally disposed 115 flanges 18 and 18^a on its opposite faces. The longitudinally extending somewhat tapered ribs, bosses or protuberances 28, as illustrated in the section in Fig. 5, are disposed between the part 10^a and the flange 18^a and 120 act to support the web 16 at this point. The vertical portions of the side bars terminate short of the butt end 12 of the part 10 of the body A, permitting fish plates D to be bolted to the opposite side faces of the butt 125 end of part 10, these fish plates extending parallel to the opposite side faces of the projecting portion 13 of part 10 in the usual manner for the attachment of rails E between the part 13 and these fish plates D. 130

It will be seen that I have provided a frog formed in sections, the middle section being so formed as to provide all the tread surface necessary to the frog, this middle section being reversible as regards its upper and under faces so that after the tread surfaces have been worn down unduly, the body section may be reversed to present new tread faces. It will be seen that in all essential respects the frog is like the frogs ordinarily found on railways and that it functions in the same manner, but that the thin portions of the body of the frog are supported against the weight of the rolling stock by the fillers 28, 29 and 32. It will be seen also that the lateral section or splice bars of the frog are interlocked with the body of the frog so that shearing strain is taken off the bolts and that this shearing strain is further eliminated from the bolts because of the fact that the body of the frog is fully supported by the fillers 28, 29 and 32 and by the protuberant middle portion 10 of the frog.

Attention is to be called to the fact that in my frog, there are but three sections and three sections only and that this frog is not what is technically known as a rail-bound frog, that is a frog, the lateral sections of which are formed of rails. In my construction, as will be evident from Figs. 3, 4, 5 and 6, the uppermost face of the middle section A is at all times above the upper edge faces of the lateral sections B and C so that under no circumstances are these lateral sections worn down under the action of the train wheels. Therefore when the middle section A has its upper face worn down to a degree rendering the reversal of the frog necessary, and the frog is reversed, the face of the previously under section now turned upward is again above the upper edge faces of the lateral sections B and C. Were the lateral sections composed of rails which eventually merged into the rails of the track on a level with the upper face of the middle portion of the frog, then the middle portion of the frog would wear downward and the wheels would also wear downward the upper edge faces of the lateral sections. Then when the middle portion of the frog was reversed, the middle portion of the frog would stand above the worn faces of the rails, which might or might not be a very dangerous condition, depending upon the extent to which these lateral rails were worn. In my construction it will be seen that the lateral sections B and C have no tread faces, in other words that all of the tread faces of the frog are on the middle section and that under all circumstances this middle section stands up higher than the upper edge faces of the lateral sections. It is further to be noted that the middle section is supported by the tongues 20 of the lateral sections as

well as by the portions 28, 29 and 32 so that no strain comes upon the bolts 15. If the middle portion of the frog were not supported by the tongues 20 and by the upwardly projecting parts 28, 29 and 32, then when the middle section of the frog was worn and reversed, the lower face of this middle section would not touch the ground or be otherwise supported, and as a consequence all strain would come upon the bolt. 75

In my construction further, the weakest part of the frog is the heel 13, but it will be noted from Fig. 1 that the rails E fit up against this heel block and receive the tongue of the heel block, and that splice bars D, as shown in Fig. 6, rest on the inclined surfaces of the parts 26^a and these splice bars with the supporting lugs 29 act to hold the heel of the frog so that the worn surface of this heel will not rest upon the frame. The splice bars extending over the middle portion of the frog and extending parallel to the heel block 13 will give this heel block the much needed support it requires. All reversible frogs after the wear face is worn are very liable to become warped and twisted unless they are suitably supported after reversing and a solid foundation provided for the base of the frog to rest on. Such a foundation and support is provided at all 95 times in my improved frog.

I claim:—

1. A frog formed of an integral middle section and two lateral supporting sections, the middle section being reversible top to bottom and having upon its opposite faces all of the wheel supporting tread portions of the frog, the tread portions of the middle section extending above the upper edges of the lateral supporting sections in all positions of the middle portion. 105

2. A frog formed of a middle section and two lateral sections, the middle section being reversible and being formed on both faces with tread portions of the frog, the lateral sections carrying filling pieces disposed beneath the thin portions of the middle section between said bearing portions. 110

3. A frog formed of a middle section and two lateral supporting sections, the middle section being reversible and having thereon all of the wheel supporting portions of the frog, the lateral sections and the middle section being formed on their confronting edge faces with coacting, longitudinally extending, closely fitting tongues and grooves, and bolts passing through the lateral sections and through the middle section and holding them in engagement with each other, the tongues and grooves supporting the middle section, and said middle section having its upper tread faces at all times disposed above the level of the upper edges of the lateral sections. 120

4. A frog formed of a middle section and 130

two lateral sections, the middle section being reversible and having thereon the wheel supporting portions of the frog, the lateral sections and the middle section being formed 5 on their confronting edge faces with coacting longitudinally extending tongues and grooves, and bolts passing through the lateral sections and through the middle section and holding them in engagement with each 10 other, said lateral sections being formed to provide inwardly projecting webs extending beneath the middle section, the webs being provided with inwardly projecting protuberant portions acting as fillers and disposed between the bearing portions of the 15 middle section and acting to support the middle section.

5. A frog formed of a middle section and two lateral sections, the middle section being formed on each of its faces with a longitudinally extending tapering medially disposed bearing portion and laterally of this medial portion on each face with longitudinally extending converging bearing flanges 20 extending in proximity to each other beyond the tapering middle portion and then diverging, the middle portion of said flanges being spaced from each other, said middle portion being formed with transversely extending bolt holes, and lateral sections fitting against the side edges of the middle section and having perforations for the passage of bolt holes, one of said lateral sections having an integral horizontal web adapted 25 to extend beneath one end of the middle section and having a longitudinally extending rib adapted to fill the space between the lateral bearing flanges of the middle section, both of said lateral sections adjacent one end 30 being formed with inwardly extending webs adapted to extend beneath the middle section, each of said webs having a longitudinally extending rib adapted to fill the spaces between the tapered medially disposed bearing portion of the middle section and the laterally disposed flanges thereof, and bolts 35 passing through the three sections and holding them together.

6. A frog formed of a middle section and two lateral sections, the middle section being formed on each of its faces with a longitudinally extending tapering medially disposed bearing portion and laterally of this medial portion on each face with longitudinally extending converging bearing flanges 40 extending in proximity to each other beyond the tapering middle portion and then diverging, the middle portion of said flanges being spaced from each other, said middle portion being formed with transversely extending bolt holes, and lateral sections fitting 45 against the side edges of the middle section and having perforations for the passage of bolt holes, one of said lateral sections

having an integral horizontal web adapted 65 to extend beneath one end of the middle section and having a longitudinally extending rib adapted to fill the space between the lateral bearing flanges of the middle section, both of said lateral sections adjacent one end 70 being formed with inwardly extending webs adapted to extend beneath the middle section, each of said webs having a longitudinally extending rib adapted to fill the spaces between the tapered medially disposed bearing portion of the middle section and the laterally disposed flanges thereof, and bolts 75 passing through the three sections and holding them together, the confronting faces of the lateral sections and the middle section being formed with interlocking tongues 80 and grooves.

7. A frog formed of a middle section and two lateral sections, the middle section being formed on each of its faces with a longitudinally extending tapering medially disposed bearing portion and laterally of this medial portion on each face with longitudinally extending converging bearing flanges extending in proximity to each other beyond the 90 tapering middle portion and then diverging, the middle portion of said flanges being spaced from each other, said middle portion being formed with transversely extending bolt holes, and lateral sections fitting against 95 the side edges of the middle section and having perforations for the passage of bolt holes, one of said lateral sections having an integral horizontal web adapted to extend beneath one end of the middle section and having a longitudinally extending rib adapted to fill the space between the lateral bearing flanges of the middle section, both of said lateral sections adjacent one end being 100 formed with inwardly extending webs adapted to extend beneath the middle section, each of said webs having a longitudinally extending rib adapted to fill the spaces between the tapered medially disposed bearing portion of the middle section and the laterally disposed flanges thereof, and bolts 105 passing through the three sections and holding them together, the confronting faces of the lateral sections and the middle section being formed with interlocking tongues and grooves, the middle portion of the middle section at its large end being provided with a rail engaging extension having its opposite surfaces depressed below the opposite 110 surfaces of the middle section, the middle section being recessed in alinement with the upper and lower surfaces of this extension and the lateral extensions having at their corners ribs adapted to be disposed within 115 said depressed portion of the middle section.

8. A frog formed of a middle reversible section and two lateral sections formed to

support the middle section in either of its positions and with its tread faces above the upper edges of the lateral sections, said lateral sections having base flanges extending 5 outward beyond the upper portions of the lateral sections whereby they may be spiked to the railbed.

9. A reversible frog composed of a reversible middle section having upon its opposite faces all of the tread faces of the frog and two lateral sections conterminous with the middle section, the lateral sections being provided with longitudinally extending, inwardly projecting tongues, the middle 15 section having on each edge face longitudinally extending recesses into which said tongues fit, said lateral sections having webs extending beneath the middle section and formed with supporting lugs fitting the 20 spaces between the tread faces of the middle section and against the bottom of said spaces,

and bolts passing through the lateral sections and the middle section.

10. A frog of the character described comprising a middle reversible section formed 25 with the tread faces of the frog and lateral sections, the heel end of the middle section being formed with an outwardly widening heel, the lateral faces of which are formed with longitudinally extending tongues 30 adapted to extend between the heads and flanges of abutting rails, splice bars engaging in lateral grooves on the body of the middle section adjacent said heel and extending parallel to the heel whereby rails 35 may be received between the heel and said splice bars, and bolts passing through the splice bars and the heel.

In testimony whereof I hereunto affix my signature.

RICHARD P. WEAVER.
